(57) CLAIM

The ornamental design for a portable cosmetic case, as shown and described.

DESCRIPTION

FIG. 1 is a bottom, front and right side perspective view of our new design wherein the portable cosmetic case is in a closed condition;

FIG. 2 is a bottom plan view thereof;

FIG. 3 is a top plan view thereof;

FIG. 4 is a right side elevational view thereof;

FIG. 5 is a left side elevational view thereof;

FIG. 6 is a front elevational view thereof;

FIG. 7 is a rear elevational view thereof; and,

FIG. 8 is an interior, front and right side perspective view of our new design wherein the portable cosmetic case is in an open condition.
